US00D964487S

(12) **United States Design Patent** (10) Patent No.: **US D964,487 S**
(45) Date of Patent: **** Sep. 20, 2022**

(54) **SPHERICAL DYNAMIC RESISTANCE TOOL**

(71) Applicant: **The Wild Gym Company LLC**, Niwot, CO (US)

(72) Inventors: **David Hunt**, Coram, MT (US); **Daniel Vinson**, Lafayette, CO (US)

(73) Assignee: **THE WILD GYM COMPANY LLC**, Louisville, CO (US)

(**) Term: **15 Years**

(21) Appl. No.: **29/735,045**

(22) Filed: **May 18, 2020**

(51) LOC (13) Cl. **21-02**

(52) U.S. Cl.

USPC **D21/680**

(58) **Field of Classification Search**

USPC D21/680, 691, 498; D30/160; D9/428; D11/222, 17

See application file for complete search history.

(57) **CLAIM**

The ornamental design for the spherical dynamic resistance tool, as shown and described.

DESCRIPTION

FIG. 1 is a perspective view of the spherical dynamic resistance tool;

FIG. 2 is a right-side view thereof;

FIG. 3 is a left-side view thereof;

FIG. 4 is a front view thereof;

FIG. 5 is a back view thereof;

FIG. 6 is a top view thereof; and,

FIG. 7 is a bottom view thereof.

The broken lines shown in the drawings depict portions of the spherical dynamic resistance tool that form no part of the claimed design.
